Patented Jan. 9, 1917.

UNITED STATES PATENT OFFICE.

MAYER DAXE, OF NEW YORK, N. Y.

SPRING BED-BOTTOM.

1,211,922.

Specification of Letters Patent.

Patented Jan. 9, 1917.

Application filed February 16, 1915. Serial No. 8,470.

To all whom it may concern:

Be it known that I, MAYER DAXE, a citizen of the United States, and a resident of the borough of Manhattan, city, county, and State of New York, have invented certain new and useful Improvements in Spring Bed-Bottoms, of which the following is a specification.

My improvements relate to means for supporting spring bed bottoms on bedsteads.

Heretofore the elastic resilient mattress support constituting the bed bottom has been permanently attached to a rigid rectangular frame so that the spring bottom could only be placed upon or removed from the bedstead by lifting it and its supporting frame bodily; and as the frame was necessarily heavy in order to afford the requisite degree of strength to hold the spring bottom extended and taut the services of two persons has been necessary in order to properly handle the spring bottom and its frame. Furthermore the rigid structure and size of the bed bottom frame was a disadvantage in that it was not only difficult to handle, but took up much space, and was not adapted to convenient transportation or manipulation for purposes of cleaning, &c., and added materially to the cost of the bed bottom as well as to its weight and cumbrousness.

These objections I obviate by my invention which is designed to afford a light weight elastic resilient bed bottom which may be detachably secured directly to the bedstead and expeditiously applied or removed therefrom, and which when detached may be rolled up for transportation or storage, or conveniently manipulated for purposes of cleaning, &c. And all this may be accomplished by one person alone.

The invention consists in the combination, construction and arrangement of parts herein described and claimed specifically, distinctive features being the dispensing with the side members of the spring bottom frame, or more correctly with any frame therefor at all,—the elastic resilient support for the mattress being attached simply to end bars or rods; and the provision of means whereby said elastic resilient mattress support may be detachably secured to the end cross bars of the bedstead frame, all as hereinafter more fully set forth.

In the accompanying drawings, Figure 1, is a top view, more or less diagrammatic, representing the practical application of my invention; Fig. 2, is a sectional elevation

upon a larger scale showing the structure and illustrating the operation of one of my bed bottom tightening and securing devices; 60 Fig. 3, a top view of the parts shown in Fig. 2; Fig. 4, a sectional elevation in detail of one of the bed bottom end holders; Fig. 5, a top view of the parts shown in Fig. 4; Fig. 6, is a detail view of a portion 65 of one of the end cross bars of the bed bottom.

F, represents a bed frame of any ordinary or desired construction, of which f, f, are the corner posts, f', f', the end cross bars 70 or members extending between and attached to said posts, and f², f², the longitudinal members of the frame also connecting said end posts f, f. The end cross bars are usually rectangular in cross section and I have here- 75 shown and described them as of "angle iron" structure, although this is not an absolutely essential feature since other forms in cross section of the end frame bars f', f', may be utilized for my purpose. 80

My bed bottom B, consists of the spread or mattress-supporting surface b, attached at its cross edges to the intermediate plates or bars b', b', and the tension springs b², b², and end cross bars b³, b³—the tension 85 springs b², b², being interposed between and attached to the intermediate bars b', b', and the end cross bars b³, b³. The structure of the spread b, is not material. It may be of spirally woven wire fabric or any construc- 90 tion found most expedient,—the tension springs b², b², being relied upon, for the purposes of my invention, to afford the requisite degree of elasticity and resilience in use.

As before mentioned the usual longitudi- 95 nal members between the end cross bars b³, heretofore constituting therewith a rigid frame for the mattress support, are omitted, so that the latter when detached from the bed frame F, may be folded or rolled up 100 within a comparatively small compass, or conveniently manipulated for purposes of cleaning, &c. The omission of these longitudi- 105 nal members of the bed bottom is an important factor in the case since it materially reduces the weight of the bed bottom and simplifies the structure as a whole, so that a single person can easily handle and manipulate the bed bottom for all practical purposes. 110

In order to detachably connect the bed bottom B, with the bedstead frame F, I provide hook members H, preferably attached to the cross member f', at the foot

of the bed, and tightening devices T, preferably attached to the cross member f', at the head of the bed, although this arrangement is not material, and may be reversed if desired, as found most convenient under the circumstances and conditions of use. These holding members H, and the tightening devices T, may be permanently incorporated with the cross bars f', f', of the bed frame F, if desired, although in adapting them for use on bed frames already in existence or as ordinarily manufactured, I prefer to make both the holding and the tightening devices separate from both the bed frame and from the bed bottom. This however is a matter of choice and does not affect the operation of the parts. Again, two holders H, H, and two tightening devices T, T, may be provided, or more if found expedient in the case of wide beds. When detachably secured to the bedstead frame, the holders H, are formed with hooks h, and the tightening devices T with hooks t, which hooks fit the under sides or edges of the end cross members f', f', of the bedstead, as shown more particularly in Figs. 2, and 4. Each holder H, is also formed with a shoulder or bearing h', to rest on the top of the cross bar f', and with a cross head h², formed with a rear extension h³, adapted to enter a recess b⁴, formed for its reception in an end cross member b³, of the bed bottom B, as shown more particularly in Fig. 4. In like manner the fulcrum member t', of each tightening device T, rests upon the top of its bed frame end cross member f'; and the hook end t³, of its tightening lever t², is adapted to enter a slot or recess b⁴, formed for its reception in said end cross member b³, of the bed bottom as shown clearly in Fig. 2, of the drawings. Each tightening lever t², is pivotally connected, as at t⁴, Figs. 2, and 3, to the fulcrum member t', the inner end t⁵, being used as a handle. Attached to the fulcrum member t, is a spring latch t⁶, for engagement with a shoulder t⁷, on the end of the hook arm t⁸, for the purpose of holding the tightening lever t², t⁸, t⁵, in its depressed position, as shown in solid lines in Fig. 2, the other or raised position being shown therein in dotted lines.

The operation will be readily understood. The holding devices H, and tightening devices T, being in position on the end cross members f', of the bedstead, whether temporarily or permanently so situated, one of the bed bottom end cross bars b³, is coupled to the holders H, by passing the ends h³, of the latter through the recesses b⁴, in the cross bars, as illustrated in Fig. 4. At the other end of the bedstead, each tightening lever t², being elevated into approximately the position shown in dotted lines in Fig. 2, the end cross bar b³, at this extremity of the bed bottom is connected with the levers t²,

by passing the hook ends of the latter through the recesses b⁴, in said end cross bar b³, of the bed bottom, and then each lever t², by means of its handle member t⁵, is brought into a substantially horizontal position as shown in solid lines in said Fig. 2, the spring latch t⁶, in each case locking the lever automatically. During the operation of lowering the levers t², the tension springs b², are stretched by reason of the contact of the bed bottom end cross bar b³, with the shoulder t⁸, on said lever t², the depression of the lever being limited by contact of the stop t⁹, with a stationary part, as for instance the fulcrum member t',—thereby drawing all parts of the bed bottom taut for use. When it is desired to remove the bed bottom B, from the bedstead the latches t⁶, are pressed back from the shoulders t⁷, on the hook ends t³, of the tightening levers t², when the resilience of the springs b², will draw the levers t², up again into the position indicated in dotted lines in Fig. 2, so that the end cross piece b³, of the bed bottom may be readily withdrawn from the hook ends t³, of the levers t². This obviously slackens the whole bed bottom longitudinally so that it is an easy matter to lift the other end cross bar b³, from the holders H, at the opposite end of the bedstead. Thus released, the bed bottom B, may be folded or rolled upon itself for convenience of transportation, storage or manipulation.

My improvements are of especial importance from a sanitary point of view since they render the cleansing of the bed bottom and bedstead comparatively easy operations; and as most bedsteads are sectional and can be taken apart, the invention obviously facilitates "moving", transporting or storage, as there is no rigid heavy cumbersome bed bottom frame to take care of, or to monopolize space.

What I claim as my invention and desire to secure by Letters Patent is,

1. In combination, an elastic resilient bed bottom of the character designated, formed with end cross members connected by tension springs to the bottom spread, a bedstead frame formed with end cross bars, readily removable holders on one bedstead end cross bar adapted to engage with an end cross member of the spring bed bottom, and pivotally mounted levers adjacent opposite sides of and on the other bedstead end cross bar adapted to engage with the other end cross bar on the bed bottom, and constructed to tighten and hold the fabric permanently in place.

2. In combination, an elastic resilient bed bottom of the character designated formed with end cross members connected by tension springs to the bottom spread, a bedstead formed with end cross bars, means readily removably and detachably mounted

on one bedstead end cross bar for holding one end of the spring bed bottom, and pivotally mounted levers adjacent opposite sides of and on the other bed bottom end bar for 5 engaging with the other bedstead end cross bar and adapted to hold the spring bed bottom taut at all times, for the purposes described.

3. In combination, an elastic resilient bed 10 bottom of the character designated formed with end cross members connected by tension springs to the bottom spread, a bedstead frame with end cross bars, readily removable holders on one bedstead end cross bar 15 adapted to engage with an end cross member of the spring bed bottom, and detachable pivotally mounted levers adjacent opposite sides of and on the other bedstead end cross bar, adapted to engage with the other 20 end cross bar on the bed bottom, and constructed to tighten and hold the fabric permanently in place.

4. In combination, an elastic resilient bed 25 bottom of the character designated, formed with end cross members connected by tension springs to the bottom spread, a bedstead formed with end cross bars, readily removable means on one bedstead end cross bar for holding one end of the spring bed 30 bottom, and detachable pivotally mounted levers adjacent opposite sides of and on the other bed bottom end bar for engaging with the other bedstead end cross bar and adapted to hold the spring bed bottom taut, and 35 constructed to tighten and hold the fabric permanently in place.

5. In combination, an elastic resilient bed 40 bottom of the character designated, formed with end cross members connected by tension springs to the bottom spread, said end 45 members being formed with recesses, a bedstead formed with end cross bars, readily removable holders on one bedstead end cross bar adapted to engage with the recesses in the adjacent end cross member of the bed bottom, and pivotally mounted levers adjacent opposite sides of and on the other bedstead end cross bar, adapted to engage with the recess in the other and adjacent end cross 50 bar of the bed bottom, and constructed to tighten and hold the fabric permanently in place.

6. In combination, an elastic resilient bed 55 bottom of the character designated, formed with end cross members connected by tension springs to the bottom spread, said end 60 members being formed with recesses, a bedstead formed with end cross bars, readily removable holders on one bedstead end cross bar adapted to engage with the recesses in the adjacent end cross member of the bed bottom, and tightening devices on the other bedstead end cross bar each of said tighten-

ing devices being formed with a lever adapted to engage with the recesses in the other 65 and adjacent end cross bar of the bed bottom, and constructed to tighten and hold the fabric permanently in place.

7. In combination, an elastic resilient bed 70 bottom of the character designated formed with end cross members connected by tension springs to the bottom spread, said end members being formed with recesses, a bedstead frame formed with end cross bars rectangular in cross section, readily removable 75 holders on one bedstead end cross bar adapted to engage with the recesses in the adjacent end cross member of the bed bottom and formed with means for detachably connecting them with said rectangular end cross 80 bar of the bedstead, and tightening devices on the other rectangular end cross bar of the bedstead and formed with levers adapted to engage with the recesses in the other bed bottom end cross bar and formed with 85 means for detachably connecting said tightening devices with said other adjacent rectangular end cross bar of the bedstead, and constructed to tighten and hold the fabric 90 permanently in place.

8. In combination, an elastic resilient bed 95 bottom of the character designated, formed with end cross members connected by tension springs to the bottom spread, a bedstead frame formed with end cross bars, readily removable holding means on one bedstead end cross bar adapted to be detachably connected with one end cross bar of the bed bottom and tightening means on the other end cross bar of the bedstead frame and embodying a lever and a coöperating latch adapted to be detachably connected with the other end cross member of the bed bottom, and constructed to tighten and hold the fabric 100 permanently in place.

9. In combination, an elastic resilient bed 105 bottom having end cross members to which the bottom spread is attached, tension springs connected to the end cross members, cross bars at opposite ends of said bottom to which said springs are attached, end cross members of a bedstead frame, holders connecting one of the end cross bars to the adjacent cross member of the bedstead frame and a tightening member pivotally supported from the other end cross member of the bedstead frame and a spring latch for holding the tightening member in its horizontal position, the fulcrum member of said tightening device being detachably engaged with 110 said cross member of the bedstead frame and supporting said spring latch.

115 MAYER DAXE.
